UNITED STATES PATENT OFFICE.

WILLIAM H. H. KNIGHT, OF PHILADELPHIA, PENNSYLVANIA.

REGISTER.

1,054,214.

Specification of Letters Patent. Patented Feb. 25, 1913.

Application filed March 26, 1907. Serial No. 364,619.

To all whom it may concern:

Be it known that I, WILLIAM H. H. KNIGHT, a citizen of the United States, residing in the city of Philadelphia, in the 5 county of Philadelphia and State of Pennsylvania, have invented certain new and useful Improvements in Registers, of which the following is a specification.

While the operative parts of the invention, which is illustrated in the accompanying drawings and is hereinafter to be described, are shown as peculiarly adapted to receive movement through a single actuating shaft, it is yet to be understood, that the 10 main operative elements comprised in such device, may be employed, with equally good results, in connection with devices, wherein action of such main operative elements is brought about through actuating means, 15 other than those described, and bearing this fact in mind the invention herein described contemplates: the provision, in a device of the class named, of a compound symbol wheel bearing shaft comprising a rotatable 20 section and a non-rotatable section; means to move the rotatable section and the non-rotatable section of the shaft, successively into operative connection with any desired 25 one of a series of symbol bearing wheels supported upon said compound shaft; means to impart a rotary movement to the 30 rotatable section of said compound shaft, to turn the symbol bearing wheels thereon to the desired position; means to positively 35 determine the extent of longitudinal movement imparted to said compound shaft to move the rotatable section thereof, into operative connection with the symbol bearing 40 wheel to be turned; means to positively determine the extent of rotary movement imparted to the rotatable section of the compound shaft, to turn the symbol bearing wheels, upon said rotatable section, a predetermined 45 distance; means to lock said symbol bearing wheels against rotation independently of the compound shaft upon which they are supported; means to release the compound shaft from operative connection with the operating mechanism; means 50 whereby a single actuating shaft imparts both longitudinal and rotary movement to a compound symbol wheel bearing shaft; of means whereby a plurality of compound symbol wheel bearing shafts are caused to

operate in synchronism to move the symbol bearing wheels upon said shafts; of means whereby amounts in excess of the capacity of a symbol bearing wheel may be transferred to the symbol bearing wheel of next higher denomination; and of means for returning the several symbol bearing wheels to zero position.

To the accomplishment of the above named ends, as also of ends not above set forth, the invention consists, in the arrangement, construction and combinations of the several parts comprised therein for service, substantially as is hereinafter set forth, and illustrated in the accompanying drawings, wherein:

Figure 1, illustrates in top plan view, a register constructed in accordance with my invention: Fig. 2, shows, in side elevation, the register set forth in Fig. 1. Fig. 3, is a longitudinal vertical section, taken through the register on the line x , x , of Fig. 1, to more clearly set forth the means whereby movement is imparted to the register wheel bearing shaft. Fig. 4, is a horizontal sectional view, taken through the register on the line y , y , of Fig. 2, to more clearly set forth the construction of the register wheel bearing shaft, the register wheels thereon, and the mechanism whereby movement is imparted to said shaft. Fig. 5, is a longitudinal vertical section, taken on the line z , z , Fig. 1, through the register wheel bearing shaft, the register wheels upon said shaft, and a part of the mechanism whereby a longitudinal step-by-step movement is imparted to said shaft. Fig. 6, is a transverse vertical section taken through the register on the line m , m , of Fig. 2, looking rearward, to more clearly set forth part of the mechanism by which the register wheel bearing shaft, is moved from a lower to a higher denomination, i. e. from right to left. Fig. 7, is a transverse horizontal section, taken on the line w , w , Fig. 2, through the register, to more clearly illustrate parts of the mechanism whereby the register wheel bearing shaft is moved from a higher to a lower denomination, i. e. from left to right, in step by step movement. Fig. 8, is a longitudinal vertical section taken through the register, on the line n , n , Fig. 1, and looking in the direction indicated by the arrows marked o , to show, in part, mechanism whereby step

by step movement is imparted to the register wheel bearing shaft. Figs. 9, and 10, are detail views of parts shown in Fig. 8 to show the said parts at different points of movement. Fig. 11, illustrates, in side elevation, the register wheel bearing shaft detached from the register. Fig. 12, is a detached detail view, partly in section, of the actuating spring and connections, by and through which, the register wheel bearing shaft is moved step by step from left to right, *i. e.* from a higher to a lower denomination. Fig. 13, shows, in a plan view, a portion of the register actuating shaft, and connections therewith through which the register is moved, the said parts being shown as assembled and in position for operating the register. Fig. 14, shows in a detail view, partly in section, a portion of the mechanism shown in Fig. 13, the said parts shown as drawn asunder to more clearly show the construction thereof. Fig. 15, is a view in part elevation, and part section, taken through the parts shown in Fig. 13 on the line *o*, *o*, and looking in the direction indicated by the arrow *q*, the said view showing, in part, the mechanism through which motion is imparted, by the actuating shaft, to the devices through which the register wheel bearing shaft is moved from a lower to a higher denomination. Fig. 16, is a view in part elevation, part section, taken through Fig. 13 on line *o*, *o*, looking in the direction indicated by the arrow *p*, to show, in part, the mechanism through which a rotary movement is imparted to the register wheel bearing shaft, by the actuating shaft. Fig. 17, is a view like that shown by Fig. 16 and in which the parts are shown as they appear when being actuated. Figs. 18, 18', 19, and 20, are detail views of parts of the mechanism shown in Figs. 16, and 17, detached from the device. Fig. 21, is a view showing a modified form of one of the register wheels. Fig. 22, shows, in side elevation, the register actuating shaft, detached from the register. Fig. 23, is a longitudinal sectional view of the shaft shown in Fig. 22. Fig. 24, is a top plan view, partly in dotted outline, of my improved register, showing the said register as provided, both with a series of register wheels to show one or more independent actions, and with a series of recording wheels to register and record a number of said independent actions. Fig. 25, is an end elevation of a portion of the device shown in Fig. 24. Fig. 26, is a longitudinal vertical section, taken on the line *v*, *v*, of Fig. 24, to clearly show the transfer mechanism of the register recording wheels. Figs. 27, and 28, are detail views, in part elevation part section, to show the transfer mechanism of the register recording wheels as it appears when in action. Fig. 29, is a detached detail elevation of one of the register recording

wheels, as it appears when about to actuate the transfer device. Fig. 30, is a detail elevation of the recording wheel supporting shaft, to clearly show the means whereby the two part recording wheels are held in locked position when rotated by said shaft. Fig. 31, is a transverse sectional view taken through the recording wheel supporting shaft on the line *b*, *b*, of Fig. 30. Figs. 32, to 36, inclusive, illustrate detail views of the two part recording wheel, detached from the device. Fig. 37, illustrates, in front elevation, the transfer mechanism of my improved register.

Similar letters and numerals of reference, in the several figures of the drawings, denote similar parts.

In the present embodiment of my invention, I provide a base 1, which may be made of any suitable material, and have any desired shape or form, with uprights 2, and 3, 4, and 5, to receive the rotatable journal bearings of shafts 6, and 7, which extend transversely of the base 1, and which respectively carry and support, the one, shaft 6, a series of register wheels 8, to show the amount, or value of each single actuation of the device, the other, shaft 7, a series of recording wheels 9, whereon the sum total of any desired number of actuations of the register wheels 8, may be recorded.

I provide that the shafts 6, and 7, shall operate not only to rotate the register wheels 8, and the recording wheels 9, thereon respectively, to any desired extent, but also to lock the said register, and recording wheels against movement when the desired amounts have been respectively registered and recorded thereon, and to such end I make each of the shafts 6, and 7, compound in form, *i. e.* consisting in a part 10, which although capable of rotation, as will be hereinafter described, is yet held therefrom during the operation of the device when registering, or recording amounts upon the wheels 8, or 9, thereon, and a part 11, which is adapted to be rotated, by suitable mechanism hereinafter to be described, to turn said wheels 8 and 9.

I provide each of the sections 10, and 11 of the compound shafts 8, and 7, with a key or spline 12, and 13, respectively, to engage with either of a series of detents 14, and 15, which are formed in both the register wheels 8, and recording wheels 9, and open to the central aperture therethrough, see Fig. 26.

By the construction set forth it will be clear that the register wheels 8, or recording wheels 9, will be held from rotation, or be free to be rotated according to their position upon the rotatable, or the non-rotatable sections of the compound shafts 6, and 7.

As hereinbefore set forth the shafts 6, and 7, are each mounted in rotatable journal bearings, and of said bearings, those at one

side of the device consist of the elongated hubs 16, of gear pinions 17, and 18, through which rotary movement is simultaneously imparted to the rotatable sections 11, of the compound shafts 6, and 7, from an actuating knob or button, and to connecting mechanism, presently to be described. The remaining journal bearings 19, of each of the shafts 6, and 7, consists essentially in a flanged bushing, as shown in Figs. 4, and 5, and each thereof is held normally in fixed positions in the uprights 3, and 4, by set screws 20, and 21, see Figs. 5 and 24.

The shafts 6, and 7, are each adapted to be moved in longitudinal direction, such movement, when the shafts are employed in the same device, as shown in Fig. 24, as also the rotary movement of the section 11, of each thereof, being in unison for a purpose presently to be described.

As shown in the drawings, notably in Figs. 1, 4, 5 and 24, the register wheels 8, and recording wheels 9, are mounted upon their respective shafts 6, and 7 between the uprights 2, 3, 4, and 5, respectively, the wheels of each series being in close contact, see the figures noted.

So far as described the parts comprised in both the registering and the recording mechanism, are similar, both in construction and in action.

I will now describe the mechanism and means, by and through which, movement is imparted to the register wheel bearing shaft, and to the register wheels thereon.

To the end named, I secure uprights 23, and 24, to the base 1, in advance of, and at right angles to the uprights 2, and 3, and in said uprights 23, and 24, preferably in the plane of the shafts 6, and 7, I journal the reduced outer ends of hubs 25, and 26, the inner enlarged portions of which are in contact with each other between the uprights 23, and 24, see Figs. 3, 4, and 14. I provide the hubs 25, and 26, with alining axial bores 27, and 28, to receive a tubular shaft 29, which, journaled in said axial bores, is provided at its outer end with an enlarged head 30, having a milled surface, see Figs. 1, and 2, to insure a firm hand hold upon said head 30, when the shaft 29, is to be rotated, or moved longitudinally for a purpose presently to be explained. I provide that the hubs 25, and 26, shall be rotated by the shaft 29, and to such end I form key seats 31, and 32, in said hubs, see Figs. 3, 18, and 19, to engage short key sections 33, and 34, which project from the surface of the shaft 29, see Figs. 3, 22, and 23.

Upon the hubs 25, and 26, and between the uprights 23, and 24, I mount rotatable rings 35, and 36, and provide one thereof 35, upon its periphery, with a series of gear teeth 37, which engage with similar gear teeth formed upon a rack bar 38, which moves trans-

versely of the base 1, upon a support 39, which is secured to the upright 23, and is provided with a longitudinal groove 40, within which a rib 41, formed upon the rack bar 38, is placed and freely moves, to control, as to direction, the movement of said rack bar when the device is actuated. I provide the rack bar 38, at one end with a rearwardly projecting portion, or arm 42, and I aperture said arm to receive the reduced outer end of both the register wheel bearing shaft 6, and the recording wheel bearing shaft 7, and for the purpose of holding said shafts in rotatable connection with the arm 42, as well as for a further purpose which will presently be explained, I provide each of said shafts 6, and 7, with a milled head 43, and 44, which rigid, each with its particular shaft, bears lightly against the arm 42, thus holding said shafts in position, see Figs. 1, 4, and 24.

From the above described construction of parts, it will be apparent that movement of the rack bar 38, and its connected arm 42, in the direction indicated by the arrow *a*, see Figs. 1, 6, and 24, through the rotation of the ring 35, will operate to move the shafts 6, and 7, in longitudinal direction, and thus bring the rotatable section of each of the shafts into operative connection with any desired one of the register wheels, and the recording wheels upon said shafts; it will further be apparent that, regarding that side of the device above which the actuating button 30, is arranged, as the front of the device, the shafts 6 and 7 will be moved from right to left, whereby it will be seen that the rotatable sections 11 of said shafts are successively, and positively brought into contact with register wheels, and recording wheels of higher denomination. I deem this result to be of very great importance for reasons which will be herein-after set forth.

I provide that the ring 35, shall be actuated to move the rack bar 38, by the rotation of the shaft 29, and to such end I provide said ring 35, upon its inner surface, with a series of ratchet teeth 45, to engage the beveled end of a sliding pawl 46, which is placed and moves within recesses formed in the rear face of the hub 25, see Fig. 15. By reference to Figs. 15, 18, 19, and 20, one of which, Fig. 19, shows the recessed end of the hub (in elevation) upon which the ring 35, is mounted, it will be seen that the said hub is provided in its face, and about its axial bore, with an annular recess 47, within which the curved body 48, of the sliding pawl 46, is placed and moves, and with laterally projecting recesses 49, and 50, within which the alining end 51, and 52, of the sliding pawl is placed and moves, see Fig. 15. I provide that the pawl 46, shall be maintained in engagement with the ratchet

teeth of the ring 35, by a spring 53, which, pivoted within the hub 25, in a recess 54, formed therein, extends thence below and bears upon the end 51, of the pawl 46, see 5 Figs. 3, and 15.

It will be observed that the rotation of the ring 35, is consequent only upon the rotation of the shaft 29, toward the right, indicated by the arrow *e*, Fig. 15, at which 10 time the pawl 46, is in engagement with the ratchet teeth of ring 35, see said Fig. 15, and that when said ring 35, has been turned a sufficient distance to move the shafts 6, and 7, through the medium of rack bar 28, 15 and arm 42, as herein noted, to such position that the rotatable sections 11, of said shafts are in contact with the register wheel, or recording wheel that is to be first actuated, the said pawl 46, may be wholly withdrawn 20 from engagement with the ratchet teeth of the ring 35, by the inward movement of the operating shaft 29; the which movement operates to move key 33, upon said shaft 29, above the inner end of the 25 alining portion 52, of the sliding pawl 46, thus withdrawing the pawl from the ring as will be seen.

I provide that the particular register wheel, or recording wheel with which the 30 rotatable section 11, of the shaft 6, or shaft 7, is in operative contact shall be shown at all times, to which end I provide the rotatable ring 35, with a scale 55, so that when said ring is turned, it is only necessary to 35 bring the numeral 56, which denotes the register or recording wheel desired, to a point indicated by a pointer 57, to accurately determine the wheel to be actuated.

It is to be understood that the shafts 6, 40 and 7, are moved from right to left, *i. e.* from a lower to a higher denomination, consequently the numeral 1, upon the ring 35, indicates the units wheel, the numeral 2, the tens wheel, the numeral 3, the hundreds 45 wheel, and so on throughout the wheels mounted upon the register and recording wheel shafts.

Having set forth the means whereby the rotatable section 11, of each of the compound shafts 6, and 7, is moved into engagement with the register wheel, or the recording wheel which is first to be actuated, I will now proceed to describe the means whereby said wheels are actuated. *i. e.* rotated to bring the desired numeral thereon to a predetermined position for observation, or into position for printing.

To the end above noted I provide the rotatable ring 36, upon the hub 26, with a series of ratchet teeth 58, which are adapted to be engaged by the beveled end of a sliding pawl 59, that is placed and moves in a recess 60, formed in the forward face of the hub section 26, a spring 61, maintains the 65 pawl in engagement with the ratchet teeth

of the ring 36, until said pawl is withdrawn from such engagement by the key 33, of the operating shaft 29.

It is to be understood that the ratchet teeth of the rings 35, and 36, are similar in construction, that is to say, the teeth thereof extend in the same direction when the rings are placed side by side, as shown in Figs. 15, and 16, consequently when said rings are placed in operative position in the device, 70 *i. e.* turned face to face, as shown in Figs. 13, and 14, the teeth of the one ring will be arranged opposite to those of the other ring, so far as regards the bearing faces of said teeth, whereby it will be clearly seen 80 that the rotation of the operating shaft 29, backward and forward, will cause one of said rings to turn in one direction, and the remaining ring to turn in the opposite direction, thus, when the shaft 29, is turned 85 toward the right hand, (the upper surface of said shaft to show such movement) the ring 35, will be turned in the direction indicated by the arrow *u*, Fig. 13, the ring 36, remaining stationary during such movement; in like manner the rotation of the shaft 29, toward the left hand will operate 90 to turn the ring 36 in the direction of the arrow *t*, Fig. 13, the ring 35, now remaining stationary. It will also be understood 95 that the recesses in the hubs 25, and 26, are in form and arrangement similar, each to the other; also that the pawls 46, and 59, are similar each to the other, both in construction and in operation.

I provide the ring 36, upon its rear side with bevel gear teeth 62, to engage the teeth of a pinion 63, the elongated hub 64, of which extends outwardly and is journaled in a support 65, projecting from the base 1, 105 see Fig. 4, I provide the hub 64, with an axial bore 66, to receive a short shaft 67, which extends through said hub and is rigidly secured, at its inner end to the upright 24, which supports the hub 26, see Fig. 4. 110 I preferably reduce the outer part of the shaft 67, in diameter, and also enlarge the axial bore of the hub 64, about said reduced portion of the shaft to provide an annular space, or pocket 68, within which I place a 115 coiled spring 69, one end of which (the inner) I secure to the hub 64, while the opposite end of said spring is secured to a collar 70, that is held rigid with the shaft 67, by a nut 71, see Fig. 4.

By the construction of parts above described it will be seen that rotation of the pinion 63, by the operating shaft 29, through the medium of the ring 36, will operate to increase the tension of the spring 69, and that such tension will operate to return the pinion to its normal position when said pinion is freed from the pressure of said shaft 29, and ring 36.

Upon the hub 64, of the pinion 63, I 130

- mount a spur gear wheel 72, preferably securing said wheel in position upon said hub 64, by a key or spline as shown in Fig. 2. I provide that the gear wheel 72, shall engage with and rotate the gear pinion 17, the elongated hub of which is mounted in the upright 2, and is apertured for the reception of the compound register wheel bearing shaft 6, as hereinbefore described.
- 10 I provide that the gear pinions 17, and 18, by which rotation is imparted to the compound shafts 6, and 7, shall move in unison, and to such end I connect such gear wheels by a pinion 73, see Figs. 24, and 25.
- 15 I provide that the extent of rotation of the shafts 6, and 7, shall be accurately determined and controlled, and to such end I provide the spur gear wheel 72, upon its outer face with a flange 74, cylindrical in
- 20 form and of like diameter with said wheel, and I provide the periphery of said flange 74, with a scale 75, accurately spaced and having its dividing lines numbered in proper consecutive order as shown; a
- 25 pointer 76, which is secured to the support 65, shows extent of rotation of the wheel 72.
- From the foregoing explanation of the construction of the parts, and the operation of the same, so far as has been described, it
- 30 will be apparent that rotation of the actuating shaft 29, toward the right hand will operate to move the numeral wheel bearing shafts 6, and 7, in the direction indicated by the arrow *a*, see Figs. 1, 4, and 24, and
- 35 the rotatable section 11, of each of said shafts, into operative connection with any desired one of the register, or recording wheels 8, and 9, through the operative elements connecting said shafts 6, and 7, with
- 40 the actuating shaft 29, as described; also that the rotation of the shaft 29, toward the right hand, (the upper surface of the shaft to show direction of movement) will
- 45 through the pinions 17, and 18, upon the shafts 6, and 7, and the operative elements connecting the said pinions with the shaft 29, turn the said register wheels 8, and recording wheels 9, to bring the desired numerals upon the wheels named, to a predetermined point for observation, or into position for printing. It will also be understood that the longitudinal movement of the shaft 29, will through contact of the key 33, upon said shaft, with the sliding pawls 46,
- 50 and 59, move said pawls from engagement with the ratchet teeth of the rings 35, and 36, and thus permit said rings, and their connected mechanism, to return to normal starting position, when under spring compression, as is the case with the ring 36, as hereinbefore described.

I provide that the rack bar 38, and its connected shafts 6, and 7, be moved outwardly against the pressure of a spring, so that it

shall, when released from restraint, return to normal position, together with its connected shafts 6, and 7, and ring 35, to which end I connect one end of a sliding bar 77, with the arm 42, which moves the shafts 6, and 7, and I provide the opposite end of said bar with a support 78, which is secured to the upright 2, see Figs. 1, 2, and 7. I provide the forward edge of the bar 77, with a series of gear teeth 79, which engage with the teeth of a pinion 80, the elongated hub 81, of which is provided with an axial bore and is mounted, within a casing 82, (of which the pinion 80 forms the cap, or cover, see Fig. 12), upon a stud 83, a spring 84, surrounds the hub 81, and is connected at its opposite ends respectively to the hub 81, and the casing 82, to exert pressure upon the bar 77, and its connected rack bar 38, in the direction of the arrow *m*, see Fig. 7.

I provide that the rack bar 38, and its connected shafts 6, and 7, shall be moved backward by the spring 84, as above described, in step by step motion, and to such end I provide the sliding bar 77, with a rearwardly projecting stud 85, which successively engages each of a series of stops 86, that extend in spiral direction about a shaft 87, the reduced ends 88 and 89 of which are journaled in the uprights 2, and 3, below the shaft 6, see Figs. 3, and 5.

To maintain the stud in engagement with the stops 86, I provide that one of the reduced ends 89, of the shaft 87, shall extend outwardly from its bearing in the upright 2, and into a spring casing, 90, which is formed upon the upright noted, and within said casing, about the end 89, I arrange a coiled spring 91, the opposite ends of which are secured respectively to the shaft end 89, and side of the casing 90, the said spring thus exerting the necessary rotary pressure upon the shaft 87, to not only insure the proper engagement of the stud 85, with stops 86, but also to rotate the shaft to bring the proper stop thereon into engagement with the stud 85, when the shafts 6, and 7, have been moved longitudinally, through the medium of the rack bar 38, and its connected actuating mechanism, as hereinbefore described.

To impart step by step movement to the shafts 6, and 7, from left to right, that is from a higher to a lower denomination, it is only necessary to turn the shaft 87, backward until the stud 85, upon the bar 77, is freed from the stop 86, with which it has been in engagement, whereupon the pressure of the spring 84, (which placed under pressure by the movement of shafts 6 and 7, from right to left, now exerts pressure in the opposite direction, *i. e.* from left to right), will move the said bar 77, and its connected rack bar 38, and shafts 6, and 7, in the direction of the arrow *m*, (as hereinbefore noted) until the stud 85, contacts

with the next succeeding stop 86, as will be readily understood.

To rotate the shaft 87, backward as above noted, I provide said shaft, at one end, with 5 a series of ratchet teeth 92, to be engaged by a pawl 93, which pivoted upon a sliding bar 94, is held by a spring 95, in engagement with the ratchet teeth 92, see Fig. 8 (during the forward movement of the bar 10 94), until the rear upwardly curved end 98, of the pawl impinges against the forward upper edge of a groove 97, (formed in the upright 2, transversely of the same for the reception of the sliding bar 94), and is 15 thereby withdrawn from engagement with the ratchet teeth 92, see Figs. 9, and 10, when said ratchet has moved a distance, equal to the depth of stop 86. The sliding bar 94, extends through a supporting clip 20 98, secured to the upright 23, and has its forward end bent laterally and provided with a bifurcated portion 99, which enters a groove 100, formed in the milled head 30, of the operating shaft 29, see Figs. 1 and 2. 25 It will be observed that the pawl 93, is placed within a recessed portion of the bar 94, to which it is pivoted, and that the face of said pawl is in the plane of the face of said sliding bar, such construction to prevent contact of said pawl with the register wheels, see Fig. 5.

From the foregoing described construction of parts it will be seen that the inward pressure of the operating shaft 29, will 35 not only operate to rotate the shaft 87, to release stud 85, from stop 86, thereon, but also will withdraw both pawls 46, and 59, from the ratchet teeth of the rings 35, and 36, thus freeing said rings from the restraint of said shaft 29, and permitting them to be operated by their controlling springs, to return the rotatable sections of the shafts 6, and 7, to normal position; and to move the said shafts longitudinally a distance equal to the thickness of a register wheel, such withdrawal of the pawls consequent upon the contact of the key 33, there-with as hereinbefore set forth.

I provide that the actuating shaft 29, 50 shall be maintained at its full limit of outward movement, by spring pressure, to which end I provide the said shaft with an axial bore 101, and extend thereinto the forward end of a stud 102, which is secured 55 at its rear end to a support 103, rigid with the upright 24, a screw plug 104, closes the forward end of the axial bore 101, and between said plug 104, and the forward end of the stud 102, and bearing against each 60 thereof, at its opposite ends respectively, I interpose a coiled spring 105, see Figs. 3 and 4.

If desired the several coiled tension springs, comprised in the device as herein-before explained, may be dispensed with

and in lieu thereof springs of other construction may be employed where practical.

I provide that the total amounts of any desired number of actuations of the register wheels 8, may be transferred to, and recorded upon the recording wheels 9, in a sum, or total, to which end I first provide that the shafts 6, and 7, shall be similar, each to the other both in construction and in operation, so far as the main points of such construction and operation extend, that is to say, that the said shafts are each compound in character, *i. e.* consist of a rotatable section and a non-rotatable section, and also the said shafts are so arranged as to be moved in synchronism, that corresponding wheels thereon may be moved in synchronism, as has been hereinbefore set forth; when however it is desirable that the register wheels 8, be returned to zero position, *i. e.* their normal starting position, that new amounts may be registered thereon; and that such new amounts be recorded upon the recording wheels, in addition to the amounts already shown upon said recording wheels, it is first necessary to "reset" the register wheels, *i. e.* to return them to zero, or normal starting position, the which operation may be accomplished in the present embodiment of my invention, in 90 two ways, in one of which the operating shaft 29, is first operated to turn the ring 35, and move the shaft 6, outwardly, through the rack bar 38, and arm 42, as has been hereinbefore described, until the numeral 56, upon the ring 35, which denotes the register wheel to be first "reset" is opposite the pointer 57, at which point the shafts will be held by the engagement of stud 85, with one of the stops 86, in manner 100 and form hereinbefore set forth. The set screw 20, in the top of the upright 3, is now turned to release the flanged bushing, through which the shaft 6, moves in said upright 3, and permit the rotation of part 110 10, of said shaft, which part 10, when the wheels 8 are turned to register a given amount, is non-rotatable, as is hereinbefore set forth. The portion 10, of the shaft 6, hereinbefore noted, is now turned by rotating the head 43, until the numeral upon the wheel first to be "reset" (which wheel is indicated by the scale on ring 35), and the numeral upon the wheel next adjoining it on the part 10, are each of the same value 115 120 and arranged side by side, at which time the shaft 29, is pressed inward to rotate the shaft 87, and thus release the stud 85, from contact with stop 86, to permit the backward movement of the register shaft (longitudinally) one step by its controlling spring 84, hereinbefore noted. The part 10, of the shaft 6, is now to be again turned until like numerals adjoin as before, and again released from restraint of stop 86, and so 130

on, until all the register wheels have been reset, at which time the flanged bushing is to be again secured in stationary position by the set screw 20, to again hold the part 10, 5 of shaft 6, from rotation. The remaining method of resetting the wheels 8, consists in actuating shaft 29, to move rotatable section 11, of shaft 6, into connection with the first wheel to be reset, which wheel is indicated by the scale on ring 35, and then proceed in manner like to that followed, when registering a given number upon said wheels, turning each one forward until the zero mark upon each is in a predetermined position. 10

Having thus described the method whereby by the register wheels are returned to zero position, I will now describe the recording wheels in detail, (said wheels indicated by 20 the numeral 9,) and the means whereby transferring, or carrying (the addition of a single unit to the wheel of next higher denomination, when either of the recording wheels are turned to record a sum greater 25 than the nine digits thereon) is carried into practice.

To the end noted I preferably form each of the recording wheels 9, in two parts, a central part or hub 106, apertured to receive the shaft 7, and provided with a series 30 of detents 15, of somewhat greater depth than the corresponding detents 14, of the register wheels 8, to serve a purpose presently to be explained. The remaining part 35 of the recording wheel consists of a ring 107, adapted to closely fit upon the central part, or hub, 106, above described, and provided with a series, ten in number, of V-shaped detents to receive a locking block or 40 spur 108, which rigid with a spring 109, secured to the hub 106, operates in a recess 110, in the hub 106, which recess is practically a continuation of one of the detents 15, to the outer face of said hub, see Figs. 45 34, and 36:

The ring 107, of each recording wheel is cut away on one side to form a series, ten in number, of teeth 111, which are adapted to be contacted by a transfer pawl 112, 50 which is hinged at one end, to one arm of a bell crank lever 113, which pivoted upon a rod 114, in hinged at the outer end of its opposite arm, to a vertically movable rod, or bar 115, the upper free end of which is provided upon its 55 forward edge with an inclined portion 116, which contacting, in the upward movement of said bar 115, with the inclined back of a groove 117, within which it rests and 60 moves, is thereby forced forward into the tract of a small stud 118, which projects from the ring portion 107, of the recording wheels 9, upon the side opposite to that containing the teeth 111, see Fig. 33.

65 In Figs. 26 to 29, inclusive, the stud 118

is shown in cross section, to set forth the relation of such stud with the wheel of higher denomination, next adjoining that provided with said stud, as also its relation to the transfer mechanism of the device, as will presently be set forth.

I provide the lower end of the rod or bar 115, with a laterally projecting portion 119, the outer end of which is provided with a depending boss 120, for a purpose presently 70 to be explained. The bar or rod, 115, is normally maintained at its highest point of elevation by a spring 121, the free end of which bears upwardly upon the laterally projecting arm of the bell crank lever, 113, 80 thus holding the vertical arm of said bell crank lever in contact with a rod 122, which extends between the uprights 2, and 3, for such purpose.

I provide that the free end of the transfer pawl 112, shall move within a slot or groove 123, formed in the forward edge of a bar 124, that extends between the uprights 4, and 5. 85

It will be understood that each of the recording wheels 9, except alone the right hand, or unit wheel, is provided with a transfer pawl 112, bell crank lever 113, and vertically movable bar 115, each spring controlled as is that above described; that each 90 pawl 112, and bar or rod 115, operates in a groove 117, or 123, the first named 117, of which, are formed in a bar 125, which extends between the uprights 2, and 3, while the latter named grooves are formed in the 100 bar 124, as noted.

As hereinbefore stated the several parts last above described, constitute the transfer mechanism of the device, *i. e.* that mechanism which, when either of the recording 105 wheels 9, is rotated to record an amount, which if added to the amount already shown upon the wheel being so rotated, would equal or exceed ten units,—operates to turn the adjoining wheel of higher denomination forward, one tenth of a full revolution, to show such excess and also that an amount equal to nine units, has already been recorded upon the wheel being 110 positively turned.

Figs. 26, 27, and 28, clearly illustrate the transferring, or carrying process above noted, the first named thereof, Fig. 26, illustrating clearly the position of each of the members comprising such transferring device, and also the relation of said mechanism to the stud 118, which,—connected to the wheel under action, the which wheel is not shown in the figures now being referred to,—as it is moved downward, by the rotation of the wheel from which it projects, in the direction indicated by the arrow 128, impinges upon the upper end of bar 115, and moves said bar downward thus rocking the bell crank lever 113, and thereby 115 120 125 130

moving the transfer pawl 112, backward causing the free end of said pawl to contact with one of the teeth 111, of the adjoining wheel of higher denomination, to move the 5 same in the direction shown by the arrow 126, until the end of the laterally projecting portion of the vertically moving bar 115, comes into contact with the base 1, of the device, see Fig. 27, and said bar is therefore 10 moved from contact of said stud 118, see Fig. 28, after which the transfer mechanism will be returned to nominal position by the spring 121, see Fig. 26.

It will be understood that the ring 107, 15 only of the recording wheel 9, will be moved by the transfer mechanism, the central portion 106, remaining stationary, it being held so stationary by the key 13, in shaft 7, which key engages with one of the detents 20 15, in said central portion 106.

When the ring 107, turns upon the central portion 106, as noted, the locking block or spur 108, will be moved inwardly, the spring 109, yielding to permit of such action: 25 When however either of the recording wheels 9, are to be positively turned by the rotatable member 11, of the compound shaft 7, the parts 106, and 107, of said wheels must be positively locked against movement, so 30 far as regards each other, to which end I provide that the detents 15, in the recording wheels, shall be somewhat deeper than the corresponding detents 14, of the register wheels 8, also that the inner end of the locking spur 108, shall extend to, and normally 35 lie in the plane of the bottom of the detents 15.

As above stated, the parts of the wheel which is to be positively rotated by the 40 rotatable member of shaft 7, are to be locked together, and to such end I provide the extreme end of said rotatable member 11, of shaft 7, with a series of teeth 127, ten in number, which equi-spaced about said shaft 45 end, see Figs. 30, 31, extend outwardly beyond the outer face of the key 13, see Fig. 30, so that one of said teeth 127 (when the same are in position in the wheel, which is to be positively moved,) shall extend nearly, 50 or quite into contact with the spur 108, see Fig. 29, and thus operate to hold said spur against inward movement and in continuous engagement with the V shaped indents in the ring 107, see Fig. 29.

55 From the construction last above described it will be readily seen that the spur 108, is absolutely locked against backward movement, only upon the wheel that is to be positively moved by the rotatable section 60 of shaft 7, and further, that such locking process is accomplished only by the teeth 107, at the extreme end of the rotatable section, for the reasons set forth. It will also be observed that as the rotatable section 11, 65 of shaft 7, is provided with a key 13, which

is in engagement with one, or more of the recording wheels, (such engagement consequent upon the position of said section as regards denomination of wheel engaged by teeth 127), it follows that the wheels so engaged by the key 13, noted, will rotate with the section 11, and since each of said wheels is provided with a transfer pawl 112, bell crank lever 113, and vertically moving bar 115, such rotation will operate to move the parts named, as the same are moved during the transferring process.

To prevent action of the transfer pawls 112, bell crank levers 113, and bars 115, of those wheels which are held upon and rotated by the movable section 11, of the shaft 7, between the wheel of unit denomination, and that held upon the teeth 127, I provide means by which the movable bars 115, are disengaged from the spurs 108, before said bar has completed its full downward movement, to which end I employ a bar 128, which moves transversely of the device, in suitable guides upon the base 1, and below the laterally projecting portions 119, of the bars 115, see Fig. 26, and I connect said bar 128, to the shaft 7, to move therewith, preferably by a pendent arm 129, which extends from, and is connected to said shaft 7, see Figs. 24, and 25, and I provide 95 that the free end of this bar 128, shall lie in the vertical plane of the rotatable section 11, of the shaft 7, so that while the said bar 128, operates to move the vertically movable bars 115, of those wheels 9, which are upon 100 the rotatable section 11, of shaft 7, from connection with the studs before the pawls 112, thereof has become locked, it yet shall in no way interfere with either of the wheels upon said shaft, other than those named. 105

By reference to Figs. 26, 27, and 28, it will be observed that the back of the slots 123, in the bars 124, (within which the transfer pawls 112, move) are inclined, or beveled, as also is the lower forward portion of each 110 of said pawls, so that the said pawls shall be, at their limit of rearward motion, pressed upward and held in locked position against, and between two of the teeth 111, of the recording wheels which are being operated by said pawls. (to which end the transfer pawls are peculiarly shaped as shown) and that said wheels will thereby be held from movement until released from restraint of the pawls. 115

The operation of my improved register is very simple, and is as follows, viz: Let it be supposed that the sum of \$56.75 is to be registered and recorded upon the device. Now bearing in mind the fact that this device registers and records amounts in the order in which amounts are ordinarily written, that is to say, commencing with the numeral of highest denomination, which is that numeral farthest to the left, we find 125 130

that the first numeral of said sum \$56.75,—which sum contains four numerals,—would fall, or be registered upon the fourth wheel from the units, or right hand wheel, and 5 that to register said numeral the rotatable section 11, of the register wheel bearing shaft must first be moved into connection with said fourth wheel, to which end the shaft 29, is turned through its head 30, 10 toward the right (the upper surface of the shaft to show direction of movement); to rotate the ring 35, through its pawl connection with the shaft 29, hereinbefore described, until that division of the scale 55, 15 upon said ring, which is indicated by the numeral that corresponds with the register wheel desired, in this case numeral 4, is opposite the pointer 57, at which time the rotatable section 11, of the register wheel bearing shaft 7, will be in connection with the register wheel desired, having been moved to such position, by the movement of its connected rack bar 38, through the rotation of ring 35, as has been hereinbefore described. The rotatable section of the register shaft, now in connection with the proper register wheel, is so held through the engagement of the stud 85, with one of the stops 86, upon the spring pressed shaft 87, 20 as has been hereinbefore explained. The operating shaft 29, is now turned toward the left hand to rotate the rotatable section of shaft 7, and thus turn the register wheel which is first to be moved, through the several gear wheels hereinbefore described, until that division of the scale 75, upon the 25 spur gear wheel 72, which indicated by the numeral that corresponds with the desired numeral upon the register wheel, in this case numeral 5, is opposite the pointer 76, at which time the desired numeral 5, upon the register wheel will be in proper position for observation, or for printing, as desired. The shaft 29, is now pressed inwardly to rotate the spring shaft 87, through the sliding bar 34, connected to move with said shaft, and pawl 93, pivoted on said bar to engage the ratchet teeth 92, on the shaft 87, as hereinbefore described, and thus move the stop 86, 30 on said shaft from engagement with the stud 85, upon which the bar 77,—which it will be remembered is connected to the rack bar 38, by which the register shaft is moved,—will be moved, and will move the register shaft, through spring 84, toward the right a distance corresponding with the thickness of a register wheel, and until the stud 85 again comes into contact with the next succeeding stop 86, of shaft 87, as hereinbefore described. Further inward movement of the shaft 29, will operate through the key 33, thereon to release the ring 36, (by which movement is imparted to the gear which rotates the register shaft) from engagement through pawl 59, with said shaft 35

29, and thus permit the gears to be returned, by the spring 69, to normal position, as has been hereinbefore described. The operating shaft 29, is to be released from inward pressure, and permitted to be returned to normal 70 position by its spring 105, after which the said shaft is to be again turned to the left, to rotate the register wheel now in operative connection with the rotatable portion 11, of the register wheel bearing shaft, to 75 bring the desired numeral thereon, in this case, numeral 6, into proper position for observation, or printing, and cause the rotatable section 11, of said shaft 7, to come into operative connection with the next 80 wheel to be turned to bring the numeral 7, thereon into proper position for observation, or for printing, and finally the units wheel is turned in like manner to that above described, to bring the last numeral 5, of the 85 sum \$56.75, into proper position for observation, or for printing whereupon inward pressure upon the shaft 29, will release the stud 85, from engagement with the last stop 86, upon shaft 87, and thus permit 90 the rotatable portion 11, of the register wheel bearing shaft to wholly pass from engagement with the register wheels, see Fig. 4, and all the remaining operative parts to return to normal position. 95

The manner in which the several register wheels are reset, *i. e.* returned to normal zero position, has been hereinbefore described, and hence a recapitulation of the same is not necessary at this time. 100

While I have not herein described, and have not in the drawings forming a part hereof, shown any method, or means whereby an imprint of the amounts shown upon the register wheels, or the recording wheels 105 may be made, I yet desire to state that the device herein shown, may be used in connection with any already known method, or means for attaining the end named.

It is to be understood that the register 110 shaft, and its contained register wheels, may be used singly, as shown in Fig. 1, or in connection with a recording shaft and its contained recording wheels, as shown in Fig. 24, and when the latter named construction is employed the said shafts operate synchronously, both as to longitudinal and to rotary movement, the wheels thereon when positively acted upon to be moved, partaking of such synchronous movement. 115

It will be observed from the foregoing described construction, and operation of my improved registering, and recording device, that amounts to be registered, or recorded thereon, are placed upon the device in the 120 order in which they are usually written, that is to say, from left to right, *i. e.* from the highest to the lowest denomination contained in such amount, and that consequently amounts to be placed upon the device are 125 130

more readily carried in the mind, and more correctly registered and recorded upon the machine, than would be the case if such registering and recording process, were carried out from right to left, that is to say, by commencing such operation at the unit end of any amount, and working thence toward the end representing the highest denomination of such amount. It will also be observed that the operative parts of the device, are first positively set to register, or record the numeral of highest denomination in the sum, or amount, which is to be placed upon the device, that is to say, the rotatable sections of both the register wheel bearing shaft, and the recording wheel bearing shaft, (which normally remain at the full limit of their movement toward the right hand, or units side of the device) are first positively moved into operative connection with that particular register wheel, or recording wheel which contains the numeral of the highest denomination to be registered and recorded, and that thereafter the rotatable sections, of both the registering and the recording shafts, are moved automatically in step, by step motion, into connection with each successive wheel, of lower denomination, upon which a numeral of the sum, or amount is to be registered or recorded, until the said rotatable sections of the shafts are again at their normal position at the extreme right hand, or units side, of the device.

As noted herein the compound register and recording wheel bearing shafts, each fulfil a threefold function, *i. e.* that of a lock to hold the wheels thereon rigid against movement, until such movement is desired: that of an actuating device, to rotate the wheels thereon to any desired extent: and that of a resetting device, to return the wheels thereon to normal zero position. Further it will be observed that the single actuating shaft 29, likewise fulfils a threefold function, *i. e.* as a device to impart reciprocating movement to the wheel bearing shafts, to move the wheel rotating sections of said shafts into operative connection with any desired one of the wheels thereon: as a device to impart a rotary movement to the rotatable sections of the shafts 6 and 7, to turn the wheels thereon a predetermined distance: and as a device to release said wheel bearing shafts from restraint and permit them to resume normal starting position.

I deem the capability of threefold action, above noted, of both the register, and the recording wheel bearing shafts, and the actuating shaft 29, to be of very great importance in this art as I am thereby enabled to attain results which are otherwise unattainable, except through the use of a greatly increased number of operative parts.

I do not wish to limit my claims to the exact form, or construction of device illus-

trated in the drawings, and hereinbefore described, since the main operative element of said device, *i. e.* the compound register, or recording wheel bearing shaft, may be arranged to be operated in many ways not herein illustrated, or described, but yet fulfilling the threefold functions noted as fulfilled by the compound shaft herein shown: again the single operative shaft 29, may be arranged to move wheel bearing shafts not similar to those shown herein, while capable of fulfilling the threefold functions, noted as fulfilled by the shafts herein set forth, and with these facts in view, I claim any and every transposition, and arrangement of the above noted elements, *viz.* the compound shaft fulfilling as it does the functions set forth, and the actuating shaft also fulfilling a threefold function, together with such other transpositions and arrangements of the device shown, as will fulfil its purpose and intent, and fall within the scope of the claims hereto appended.

Having thus described my invention I claim, and desire to secure by Letters Patent:

1. In a register a compound shaft comprising a rotatable section to turn a register wheel and a non-rotatable section to hold a register wheel from rotation, mechanism to impart a reciprocating movement to said compound shaft and to rotate the rotatable section of said shaft, and a register wheel mounted upon said shaft to be acted upon thereby, substantially as described. 10

2. In a register a compound shaft comprising a rotatable section to turn a register wheel and a non-rotatable section to hold a register wheel from rotation, mechanism to impart a reciprocating movement to said compound shaft, independent mechanism to rotate the rotatable section of said compound shaft, and a register wheel mounted upon said shaft to be acted upon thereby, substantially as described. 10

3. In a register a compound shaft comprising rotatable and non-rotatable sections to first rotate a register wheel and thereafter to hold said register wheel from rotation, mechanism to move said compound shaft in longitudinal direction and to positively determine the extent of such movement, mechanism to turn the rotatable section of the compound shaft, and a register wheel mounted upon said compound shaft to be acted upon thereby, substantially as described. 11

4. In a register a compound shaft comprising rotatable and non-rotatable sections to first rotate a register wheel and to thereafter hold such register wheel from rotation, mechanism to turn the rotatable section of the compound shaft and to positively determine the extent to which said shaft is turned, independent mechanism to 1

move said shaft in longitudinal direction, and a register wheel mounted upon said shaft to be acted upon thereby, substantially as described.

5. In a register a compound shaft comprising a rotatable and a non-rotatable section in alignment each with the other to first rotate a register wheel and thereafter to hold said register wheel from rotation,
10 mechanism to positively move said shaft in longitudinal direction, independent mechanism to return said shaft in step by step movement to its normal starting position, and a register wheel mounted upon said shaft to be acted upon thereby, substantially as described.

6. In a register a compound shaft comprising alining rotatable and non-rotatable sections to first rotate a register wheel and thereafter to hold said register wheel from rotation, mechanism to turn the rotatable section of said shaft, mechanism to positively move the shaft longitudinally to a predetermined extent, independent means to return the compound shaft in step by step movement to its normal starting position, and a register wheel mounted upon said compound shaft to be acted upon thereby, substantially as described.

30 7. In a register a compound shaft comprising alining rotatable and non-rotatable sections, mechanism to turn the rotatable section, means to determine the rotation of said rotatable section, mechanism to positively move the compound shaft longitudinally to a predetermined extent, and independent means to return the compound shaft to its normal starting position, substantially as described.

35

40 8. In a register a compound shaft comprising a rotatable section to turn a register wheel and a non-rotatable section to hold said wheel from rotation, an actuating shaft connected to move said compound shaft in longitudinal direction, means independent of said actuating shaft to return the compound shaft to its normal starting position, and a register wheel to be acted upon by said compound shaft, substantially as described.

45

50 as described.

9. In a register a compound shaft comprising a rotatable section to turn a register wheel and a non-rotatable section to hold said wheel from rotation, an actuating shaft connected to move said compound shaft in longitudinal direction, means to positively determine the extent of such longitudinal movement, means independent of such actuating shaft connected to return the compound shaft in step by step to its normal starting position, and a register wheel to be acted upon by said compound shaft, substantially as described.

10. In a register a compound shaft comprising alining rotatable and non-rotatable

sections, an actuating shaft connected to move said compound shaft in longitudinal direction and to rotate the rotatable section of said compound shaft, and means independent of said actuating shaft to return the compound shaft longitudinally to starting position and to turn the rotatable section of said compound shaft backward, substantially as described. 70

11. In a register a compound shaft comprising alining rotatable and non-rotatable sections, a symbol bearing wheel upon said compound shaft, mechanism to bring said symbol bearing wheel into successive engagement with the rotatable section of the compound shaft to be turned thereby and with the non-rotatable section of said shaft to be held in locked stationary position, and means to turn the rotatable section of said compound shaft and move the said shaft in longitudinal direction, substantially as described. 75 80 85

12. In a register a compound shaft comprising alining rotatable and non-rotatable sections, a spline upon each of said rotatable and non-rotatable sections, a symbol bearing wheel mounted upon the compound shaft to be supported thereby and provided with indents to be engaged by the splines of said compound shaft, mechanism to move the rotatable section of the compound shaft into engagement with the symbol bearing wheel and the spline upon said rotatable section into an indent in said symbol bearing wheel, means to rotate the rotatable section of the compound shaft to turn the symbol bearing wheel thereon, and means to move the non-rotatable section of the compound shaft into engagement with the symbol bearing wheel and the spline upon said non-rotatable section into an indent in said symbol bearing wheel to hold said wheel from turning, substantially as described. 90 95 100 105

13. In a register a compound shaft comprising alining rotatable and non-rotatable sections, a spline upon each of said rotatable and non-rotatable sections, a symbol bearing wheel upon said compound shaft said wheel having indents to engage the splines upon said shaft, mechanism to move the compound shaft in longitudinal direction to bring the rotatable section of said shaft into engagement with the symbol bearing wheel and the splines upon said rotatable section into an indent in said wheel, connections to rotate the rotatable section of the compound shaft to turn the symbol bearing wheel thereon, a device to positively determine limit and control the rotation of the rotatable section of the compound shaft and the symbol bearing wheel thereon, and means to move the non-rotatable section of the compound shaft into engagement with the symbol bearing wheel and the spline upon said 130

non-rotatable section into an indent in said wheel to hold said wheel from rotation, substantially as described.

14. In a register a compound shaft comprising alining rotatable and non-rotatable sections, a spline upon each of said rotatable and non-rotatable sections, a plurality of symbol bearing wheels upon said compound shaft, mechanism to positively move the rotatable section of the compound shaft into operative connection with any desired one of said symbol bearing wheels, mechanism to rotate said rotatable section and the symbol bearing wheels thereon, a device to determine the extent of movement of the rotatable section and its contained wheels, and means to move the non-rotatable section of the compound shaft into engagement with the symbol bearing wheels and the spline upon said non-rotatable section into an indent in each of the said wheels to hold them from rotation, substantially as described.

15. In a register a compound shaft comprising alining rotatable and non-rotatable sections, a spline upon each of said rotatable and non-rotatable sections, a plurality of symbol bearing wheels upon said compound shaft, a device to positively determine the extent of longitudinal movement of the compound shaft to bring the rotatable section thereof into engagement with a desired symbol bearing wheel, a device to move said rotatable section into engagement with said wheel, mechanism to rotate said rotatable section and the symbol bearing wheels thereon, means to positively determine control and limit the extent of rotation of said rotatable section and the wheels thereon, and means to move the non-rotatable section of the compound shaft into engagement with the symbol bearing wheels and the spline upon said non-rotatable section into engagement with an indent in each of said wheels, substantially as described.

16. In a register a compound shaft comprising a rotatable section and a non-rotatable section, a spline rigidly connected to said rotatable section, a spline movably connected to the non-rotatable section to intermittently engage an indent in a symbol bearing wheel mounted upon the compound shaft, a symbol bearing wheel upon the compound shaft, mechanism to move the symbol bearing wheel successively into engagement with the rotatable and the non-rotatable sections of the compound shaft, and means to release the movable spline of the non-rotatable section from engagement with the symbol bearing wheels upon said compound shaft, substantially as herein set forth.

17. In a register a compound shaft comprising rotatable and non-rotatable sections, a spline rigid with the rotatable section, a spline movably connected to the non-rotatable section, a symbol bearing wheel

mounted upon the compound shaft and provided with indents to engage the splines means to move the wheel into engagement with the rotatable section to be turned thereby and into engagement with the non-rotatable section to be held from turning, and independent means to move the movable spline from engagement with said symbol bearing wheel, substantially as described.

18. In a register a compound shaft comprising a rotatable section and a non-rotatable section, a spline rigid with the rotatable section, a spline movably connected with the non-rotatable section, a symbol bearing wheel mounted upon the compound shaft and provided with indents to engage the splines in said compound shaft, means to move the wheel into engagement with the rotatable section, means to turn said rotatable section and symbol bearing wheel thereon, means to move the wheel into engagement with the non-rotatable section and the movable spline of said section into an indent in said wheel, and an independent device to move the movable spline from connection with the symbol bearing wheel, substantially as described.

19. In a register a compound shaft comprising alining rotatable and non-rotatable sections, an arm connected to be moved and to move said compound shaft longitudinally, a rotatable actuating shaft, and connections between said actuating shaft and said arm to move the latter and its connected compound shaft, substantially as described.

20. In a register a compound shaft comprising alining rotatable and non-rotatable sections, a spline upon each of said sections, a symbol bearing wheel upon said compound shaft said wheel having indents to engage the splines in said shaft, an arm connected to the compound shaft to be moved, and to move said shaft, a rotatable actuating shaft, connections between said actuating shaft and said arm to move the latter and bring the rotatable and non-rotatable sections of the compound shaft successively into engagement with the symbol bearing wheel, substantially as described.

21. In a register a compound shaft comprising alining rotatable and non-rotatable sections, a spline upon each of said sections, a symbol bearing wheel upon the compound shaft said wheel having indents to engage the splines in said shaft, an arm connected to the compound shaft to be moved and to move said shaft, a rotatable actuating shaft, connections between said actuating shaft and said arm to move said arm and bring the rotatable and non-rotatable sections of the compound shaft successively into engagement with the symbol bearing wheel, and mechanism to rotate the rotatable section of the compound shaft and determine

the extent of such rotation to turn the symbol bearing wheel a predetermined extent, substantially as described.

22. In a register a compound shaft comprising a rotatable section and a non-rotatable section, a symbol bearing wheel upon said compound shaft, means to withhold said symbol bearing wheel from rotation upon the rotatable or the non-rotatable sections of the compound shaft, a rotatable actuating shaft, connections between the actuating shaft and the rotatable section of the compound shaft to impart rotary movement from said actuating shaft to said rotatable section of the compound shaft, means to release the rotatable section of the compound shaft from the rotatable actuating shaft, and independent means to return the rotatable section of the compound shaft to normal starting position, substantially as described.

23. In a register a shaft to receive a symbol bearing wheel, a symbol bearing wheel upon said shaft, a rotatable actuating shaft, connections between said actuating shaft and the shaft upon which the symbol bearing wheel is mounted to rotate said latter named shaft, connections between the actuating shaft and the shaft upon which the symbol bearing wheel is mounted to impart longitudinal movement to said latter named shaft, and independent connections operated by the actuating shaft to release the symbol wheel bearing shaft from restraint of said actuating shaft, substantially as described.

24. In a register a compound shaft comprising a rotatable section and a non-rotatable section, a symbol bearing wheel upon said compound shaft, a device to hold said wheel from rotation upon the rotatable and non-rotatable sections of the compound shaft, a rotatable actuating shaft, connections between said actuating shaft and the compound shaft to move the latter named shaft in longitudinal direction, connections between the actuating shaft and the rotatable section of the compound shaft to turn said rotatable section, means actuated by the rotatable actuating shaft to determine the extent of rotation of the rotatable section of the compound shaft, and means operated by the actuating shaft to release the compound shaft from restraint of said actuating shaft, substantially as described.

25. In a register a compound shaft comprising a rotatable section and a non-rotatable section, a symbol bearing wheel upon said compound shaft, a rotatable actuating shaft, connections operated by said rotatable actuating shaft to move the non-rotatable and the rotatable sections of the compound shaft successively into operative connection with the symbol bearing wheel, a device connected to release said compound shaft from

restraint of the actuating wheel, and independent means to return said compound shaft in step by step movement to normal position, substantially as described.

26. In a register a plurality of compound shafts each comprising a rotatable and a non-rotatable section, symbol bearing wheels upon each of said compound shafts, connections to move said compound shafts in synchronism, a rotatable actuating shaft, a device moved by said actuating shaft to impart a predetermined extent of longitudinal movement to said compound shafts to bring the rotatable sections of said compound shafts into operative connection with the symbol bearing wheels upon said compound shafts, connections operated by said actuating shaft to turn the rotatable sections of the compound shafts and the wheels thereon, a device to determine the extent of rotation of said rotatable sections and the wheels thereon, and mechanism connected to return the compound shafts to normal starting position, substantially as described.

27. In a register a compound shaft comprising a rotatable section and a non-rotatable section, an actuating shaft, a device operated by said actuating shaft to positively move the compound shaft in longitudinal direction, connections to release the actuating shaft from the latter named device, a device operated by the actuating shaft to turn the rotatable section of the compound shaft a predetermined distance, a connection to release the latter named shaft rotating device from the actuating shaft, and independent mechanism connected to move the shaft rotating device to return the rotatable section of the compound shaft to normal starting position, substantially as described.

28. In a register a compound shaft comprising a rotatable section and a non-rotatable section, an actuating shaft, a device to be rotated by the actuating shaft to turn the rotatable section of the compound shaft, gear connections between said device and the actuating shaft, gear connections between said device and the rotatable section of the compound shaft, and independent means connected to return the rotatable section of the compound shaft to normal starting position, substantially as described.

29. In a register a compound shaft comprising a rotatable section and a non-rotatable section, a spline upon the rotatable section of the compound shaft, a gear pinion upon said rotatable section to be turned and to turn said rotatable section, a spur gear wheel mounted to engage and turn the pinion and its supporting rotatable shaft section, gear connections between said spur gear wheel and an actuating shaft to positively turn said spur gear wheel forward, and independent mechanism to return said

spur gear wheel to starting position when released from restraint of the actuating shaft, substantially as described.

30. In a register a compound shaft comprising a rotatable section and a non-rotatable section, a spline upon the rotatable section of said shaft, a gear pinion upon the rotatable section to be turned and to turn said rotatable section, a spur gear wheel 10 mounted to engage with and turn the gear pinion and its supporting shaft, gear connections between said spur gear wheel and an actuating shaft to be turned by said shaft to positively turn said spur gear wheel in 15 one direction, a device moved by the actuating shaft to release the spur gear wheel from restraint of said shaft, and a spring connected to return the spur gear wheel and its connected rotatable shaft section to normal 20 starting position when said spur gear wheel is released from restraint of the actuating shaft, substantially as described.

31. In a register an actuating shaft, a gear bearing ring or wheel supported upon said shaft, connections between the actuating shaft and the gear bearing ring or wheel to turn the same in one direction when the shaft is rotated, a compound shaft comprising a rotatable section and a non-rotatable 30 section, connections between the gear bearing ring or wheel upon the actuating shaft and the rotatable section of the compound shaft to turn the latter, and a device independent of the gear bearing ring or wheel 35 to return said rotatable section to normal starting position when its controlling geared ring or wheel is freed from restraint of the actuating shaft, substantially as described.

32. In a register an actuating shaft, a gear bearing ring or wheel supported upon said shaft, connections between said actuating shaft and said gear bearing ring or wheel to turn the ring or wheel in one direction when the shaft is rotated, a compound shaft 40 comprising a rotatable section and a non-rotatable section, connections between the compound shaft and the gear bearing ring or wheel upon the actuating shaft to be moved by said ring or wheel and to move 45 said compound shaft in longitudinal direction, a device connected to release the gear bearing ring or wheel from operative connection with the actuating shaft, and independent mechanism to return the compound 50 shaft to its normal starting position, substantially as described.

33. In a register an actuating shaft, a gear bearing ring or wheel supported upon said actuating shaft, connections between the actuating shaft and the gear bearing ring or wheel upon said shaft to turn said ring or wheel in one direction only when said actuating shaft is rotated, a compound shaft comprising a rotatable section and a non- 60 rotatable section, connections between the

compound shaft and the gear bearing ring or wheel upon the actuating shaft to operatively connect said ring or wheel with said compound shaft to move the same in longitudinal direction when the actuating shaft is 70 rotated, a device moved by the actuating shaft to release said shaft from the gear bearing ring or wheel upon said actuating shaft, and mechanism connected to move the compound shaft in step by step motion to 75 its normal starting position, substantially as described.

34. In a register a compound shaft comprising a rotatable section and a non-rotatable section, symbol bearing wheels upon 80 said compound shaft, an actuating shaft, a gear bearing ring or wheel mounted upon the actuating shaft and connected to move the compound shaft in longitudinal direction to bring the rotatable section of said 85 compound shaft into connection with a desired symbol bearing wheel, a gear ring or wheel mounted upon the actuating shaft and connected to turn the rotatable section of the compound shaft and the symbol bearing 90 wheel upon said shaft, devices moved by the actuating shaft to release said shaft from operative connection with the gear bearing rings or wheels mounted upon said shaft, and means independent of the actuating 95 shaft to move the compound shaft in longitudinal direction and the rotatable section of said shaft in rotary direction to normal starting position, substantially as described.

35. In a register an actuating shaft, a hub 100 upon said actuating shaft, a device to hold said hub from rotation upon said actuating shaft, a gear bearing ring upon said hub, connections between said hub and the ring upon said hub to move the ring in one direction when the actuating shaft is rotated, a symbol wheel bearing shaft adapted to move 105 in longitudinal direction, and connections between said symbol wheel bearing shaft and the gear bearing ring whereby the shaft is moved longitudinally when the actuating shaft and its supported hub and ring is rotated, substantially as described.

36. In a register an actuating shaft, a hub 110 upon said shaft, a device to hold said hub from rotation upon said shaft, a gear bearing ring upon the hub, connections between said hub and the ring thereon to move said ring in one direction only when the actuating shaft is turned, a symbol wheel bearing 115 shaft having a section adapted to be rotated, connections between the rotatable section of the symbol wheel bearing shaft and the ring upon the hub whereby said rotatable section is turned when the actuating 120 shaft and its supported hub and ring is rotated, substantially as described.

37. In a register an actuating shaft, a hub 125 upon said shaft to support a geared ring connected to be moved by its supporting 130

shaft in one direction only, a second hub upon said actuating shaft to support a geared ring connected to be moved by its supporting shaft in direction opposite the 5 geared ring first above named, a symbol wheel bearing shaft, and connections between said latter named shaft and the geared rings whereby said symbol wheel bearing shaft is reciprocated and a part thereof rotated when the actuation shaft is turned in opposite directions, substantially as described.

38. In a register an actuating shaft, a spline therein, a hub upon the actuating 15 shaft having an indent to engage the spline, a pawl upon said hub, a geared ring upon the hub provided with ratchet teeth to engage the pawl upon the hub, a compound shaft to support symbol bearing wheels, said 20 symbol bearing wheels, and connections between the gear toothed ring and the compound shaft to move the latter longitudinally when the actuating shaft is rotated, substantially as described.

39. In a register an actuating shaft, a spline therein, a hub upon the actuating shaft provided with an indent to engage the spline, a pawl upon the hub, a geared ring upon the hub having ratchet teeth to be 30 engaged by the pawl upon the hub, a compound shaft comprising a rotatable section and a non-rotatable section, symbol bearing wheels upon the compound shaft, connections between the gear toothed ring and the 35 rotatable sections of the compound shaft to turn said rotatable section when the actuating shaft is rotated, substantially as described.

40. In a register an actuating shaft, a 40 spline therein, plurality of hubs upon the actuating shaft, a pawl upon each of said hubs and connected to move each a gear toothed ring in direction opposite each to the other, a gear toothed ring upon each of said 45 hubs each of said rings having ratchet teeth to be engaged by a pawl to move said rings in direction opposite each to the other, a compound shaft comprising a rotatable section and a non-rotatable section, symbol 50 bearing wheels upon said compound shaft, connections between one of the gear toothed rings and the compound shaft to move said shaft longitudinally and the rotatable section thereof into engagement with a predetermined symbol wheel upon the shaft, and 55 connections between the remaining gear toothed ring and the rotatable section of the compound shaft to turn said rotatable section and the symbol bearing wheels thereon, substantially as described.

41. In a register a compound shaft comprising a rotatable section and a non-rotatable section, a gear toothed rack bar supported parallel with said compound shaft, 60 connections between said gear toothed rack

bar and said compound shaft to insure synchronous longitudinal movement of said rack bar and said compound shaft, an actuating shaft, and a device moved by said actuating shaft to impart movement from said shaft through the rack bar to the compound shaft, substantially as described. 70

42. The combination in a register of a compound shaft comprising a rotatable section and a non-rotatable section, a gear toothed rack bar connected to be moved and to move said compound shaft in longitudinal direction, an actuating shaft, gear connections between said actuating shaft and the rack bar to move said bar and its connected compound shaft in longitudinal direction, a device to release the rack bar and its connected compound shaft from the actuating shaft, and independent mechanism to return the connected rack bar and compound shaft to normal starting position, substantially as described. 75 80 85

43. In a register a compound shaft comprising a rotatable section and a non-rotatable section, symbol bearing wheels upon said compound shaft, an actuating shaft capable of reciprocating and rotating motion, connections moved by said actuating shaft when turned in one direction to impart longitudinal movement to the compound shaft, connections moved by the actuating shaft when turned in the opposite direction to impart rotary movement to the rotatable section of the compound shaft, and connections moved by the reciprocating movement of said actuating shaft to release the compound shaft from said actuating shaft, substantially as described. 90 95 100

44. In a register a compound shaft comprising a rotatable section and a non-rotatable section, an actuating shaft capable of reciprocating and rotating motion, connections moved by the actuating shaft to impart longitudinal movement to the compound shaft, connections moved by the actuating shaft to turn the rotatable section of the compound shaft, a shaft arranged in juxtaposition to the compound shaft, a device upon said shaft to insure a step by step movement to the compound shaft when 105 said compound shaft is moving to starting position, and connections between the actuating shaft and the compound shaft controlling device to move the latter and impart step by step longitudinal movement to said 110 compound shaft, substantially as described. 115 120

45. In a register a shaft to support symbol bearing wheels, a device to move said shaft longitudinally to a predetermined extent, a rotatable shaft journaled in the plane of and in juxtaposition to said symbol wheel bearing shaft, a series of stops upon said rotatable shaft to be successively engaged by an arm connected to move with the symbol wheel bearing shaft, said arm, means 125 130

to turn the rotatable shaft to bring the stops thereon successively into the track of said arm to be contacted thereby, and independent means to return the symbol wheel bearing shaft to normal starting position and the arm thereof into successive engagement with the stops upon the rotatable shaft, substantially as described.

46. In a register a compound shaft comprising a rotatable section and a non-rotatable section, mechanism to move said shaft in longitudinal direction, a device to determine the extent of such longitudinal movement, a rotatable shaft journaled in the plane of and in juxtaposition to said compound shaft, a series of stops arranged in spiral direction upon the rotatable shaft, an arm connected to move with the compound shaft to contact with the spirally arranged stops, a device to turn the stop bearing rotatable shaft by successive impulses, and independent means to move the compound shaft to normal starting position and the arm connected to said shaft into contact with each successive stop of the rotatable stop bearing shaft, substantially as described.

47. In a register a shaft to receive symbol bearing wheels, an actuating shaft, connections between said actuating shaft and said symbol wheel bearing shaft to positively move the latter named shaft longitudinally in one direction, a rotatable stop bearing shaft journaled in juxtaposition to said symbol wheel bearing shaft, stops projecting from said stop bearing shaft, connections between the actuating shaft and the stop bearing shaft to turn the latter named shaft by successive impulses, an arm to move with the symbol wheel bearing shaft to contact with the successive stops upon the rotatable stop bearing shaft, and means independent of the actuating shaft to return the symbol wheel bearing shaft to normal starting position, substantially as described.

48. In a register a shaft to receive symbol bearing wheels, an actuating shaft, connections between said actuating shaft and said symbol wheel bearing shaft to move the latter named shaft longitudinally in one direction only, a rotatable stop bearing shaft journaled in juxtaposition to the symbol wheel bearing shaft, a series of projecting stops extending spirally around the stop bearing shaft, connections between the actuating shaft and the rotatable stop bearing shaft to turn the latter in one direction only, a device independent of the actuating shaft to return the stop bearing shaft to normal starting position, an arm connected to move with the symbol bearing shaft to contact successively with the stops upon the rotatable stop bearing shaft to impart step by step movement to

the symbol wheel bearing shaft, and connections independent of the actuating shaft to return the symbol wheel bearing shaft to normal starting position, substantially as described.

49. In a register a rotatable stop bearing shaft, a series of stops extending in spiral direction around said shaft, a torsion spring connected to turn said stop bearing shaft in one direction, a symbol wheel bearing shaft, an arm connected with said symbol wheel bearing shaft to engage the stops upon the stop bearing shaft, means to move the symbol wheel bearing shaft in longitudinal direction, an actuating shaft, and a device moved by said actuating shaft to turn the stop bearing shaft to bring the stops thereon successively into the path of the arm of the symbol wheel bearing shaft, substantially as described.

50. In a register a rotatable stop bearing shaft, a series of stops extending in spiral direction upon the periphery of said shaft, a torsion spring upon said shaft to turn the shaft in one direction, ratchet teeth in said stop bearing shaft to be engaged by a pawl, in combination with an actuating shaft, a bar connected to be moved by said actuating shaft, a pawl upon said bar to engage the ratchet teeth of the stop bearing shaft, a symbol wheel bearing shaft, and an arm upon said latter named shaft to engage the stops of the stop bearing shaft, substantially as described.

51. In a register an actuating shaft to be reciprocated and rotated, a spring to hold said actuating shaft at its full limit of axial motion in one direction, a sliding bar connected to the actuating shaft to be moved thereby, and a pawl hinged to said sliding bar, in combination with a stop bearing shaft connected to be rotated, a series of stops upon said shaft, ratchet teeth upon said stop bearing shaft to be engaged and moved by the pawl, means to limit the engagement of the pawl with said ratchet teeth, a symbol wheel bearing shaft, and an arm connected to said shaft to contact with the stops of the stop bearing shaft, substantially as described.

52. In a register an actuating shaft, a symbol wheel bearing shaft to be moved longitudinally, and connections between said actuating shaft and said symbol wheel bearing shaft to transmit positive movement in one direction from said actuating shaft to said symbol wheel bearing shaft, in combination with a bar connected to move with the symbol wheel bearing shaft, a spring to move said bar and its connected symbol wheel bearing shaft in direction opposite that in which said shaft is moved by the actuating shaft, an arm upon said bar to successively engage stops which are moved into

the path of said arm, and means to move the stops to engage the arm, substantially as described.

53. In a register a longitudinally movable symbol wheel bearing shaft, an arm connected to said shaft to be moved and to move said shaft, a rack bar connected to said arm to be moved by an actuating shaft and to move said arm and its connected symbol wheel bearing shaft in one direction, and said actuating shaft, in combination with a bar connected to the arm and placed to move parallel with the rack bar, gear teeth upon said bar to engage a pinion, said pinion, a spring connected to turn said pinion to move the bar and its connected symbol wheel bearing shaft, an arm projecting from the bar to be moved into the path of said bar, and means to successively move a series 20 of stops to engage the arm and impart a step by step movement to the symbol wheel bearing shaft when the same is moved to normal starting position, substantially as described.

54. In a register a shaft to support a series of symbol bearing wheels said shaft comprising a rotatable section and a non-rotatable section, and symbol bearing wheels upon said shaft, in combination with an actuating shaft capable of reciprocating and rotating movement, a ring upon said actuating shaft to be moved when the actuating shaft is turned toward the right hand, connections between said ring and the symbol bearing shaft to move said shaft longitudinally when the ring is turned, a second ring upon the actuating shaft to be turned toward the left hand, connections between said latter ring and the rotatable section of the symbol wheel bearing shaft to turn said section, when the wheel is turned, mechanism connected to release the symbol wheel bearing shaft from the actuating shaft when the latter is moved longitudinally, and means 45 moved by the actuating shaft to impart a step by step longitudinal movement to the symbol wheel bearing shaft, substantially as described.

55. In a register a plurality of symbol wheel bearing shafts each to be reciprocated and rotated, connections between said shafts to determine the synchronous movement of said shafts, an actuating shaft capable of both longitudinal movement and 55 rotary movement, connections moved by said actuating shaft to impart longitudinal and rotary movement to the symbol wheel bearing shafts, a device moved by the actuating shaft to release the symbol wheel bearing shafts from restraint of said actuating shaft, and independent mechanism connected to move the symbol wheel bearing shafts in step by step motion to normal starting position, substantially as described.

56. In a register a compound shaft com-

prising a rotatable section and a non-rotatable section, register wheels upon said shaft, connections actuated to move the rotatable section and the non-rotatable section of said shaft successively into engagement with the 70 register wheels, mechanism to turn the rotatable section of the shaft and the wheels thereon to a predetermined extent, and mechanism to move the shaft longitudinally, in combination with a second compound 75 shaft comprising a rotatable section and a non-rotatable section, recording wheels upon the latter named shaft, and connections between the compound shafts to insure synchronous movement of said shafts and the 80 respective register and recording wheels thereon, substantially as described.

57. A compound shaft comprising a rotatable section and a non-rotatable section, a device to move the compound shaft in longitudinal direction, a device to turn the rotatable section of said compound shaft, mechanism to positively determine the extent of movement of said shaft both longitudinal and rotary, a device to release the compound 90 shaft from its actuating devices named, and independent mechanism to return the shaft to its normal starting position, substantially as described.

58. A compound shaft comprising rotatable and non-rotatable sections, a spline in each of said rotatable and non-rotatable sections, register wheels upon said compound shaft said wheels having indents to engage the splines in said shaft, means to hold the 100 register wheels from lateral movement, mechanism to move the rotatable section of the compound shaft into connection with a desired wheel, means to rotate said rotatable section and the wheels thereon, a device to 105 determine the extent of rotation of said rotatable section, means to return the shaft to normal starting position, and independent means to return the register wheels upon the shaft to zero position, substantially as de- 110 scribed.

59. In a register a compound shaft comprising a rotatable section and a non-rotatable section, splines in each of said rotatable and non-rotatable sections, and symbol bearing wheels upon said compound shaft and having indents to receive the splines, in combination with an actuating shaft capable of reciprocating and rotating movement, a spline in said actuating shaft, a hub upon 115 the actuating shaft and provided with a groove to receive said spline, a ring upon said hub connected to move the compound shaft when actuated by the actuating shaft, a series of indices upon said ring to co-act 120 with a pointer upon a fixed part of the device to show extent of rotary movement of said ring, and said pointer, substantially as described.

60. In a register a compound shaft com- 130

prising a rotatable section and a non-rotatable section, and symbol bearing wheels upon said shaft connected to be moved by said shaft, in combination with an actuating shaft mounted at right angles to the compound shaft, a gear wheel mounted upon the actuating shaft to be positively turned thereby in one direction, a gear wheel upon the rotatable section of the compound shaft, and gear wheels interposed between the gear wheel upon the actuating shaft and the gear wheel upon the compound shaft to impart rotary movement from the former to the latter named shafts, and means connected with one of said gear wheels to determine extent of rotation of said gear wheel and its connected compound shaft, substantially as described.

61. In a register a compound shaft comprising a rotatable section and a non-rotatable section, symbol bearing wheels upon said shaft connected to be actuated by said shaft, and a gear pinion upon the compound shaft to be turned and to turn said shaft, in combination with an actuating shaft mounted at right angles to said compound shaft, a gear wheel upon said actuating shaft to be positively turned in one direction by said actuating shaft, connected gear wheels mounted to engage the teeth of the gears upon the actuating shaft and compound shaft respectively to communicate motion from the former to the latter named shafts, a series of indices upon one of said gear wheels to co-act with a pointer upon a fixed part of the device to show extent of rotation of the shafts, and said pointer, substantially as described.

62. In a register a spur gear wheel mounted to engage and turn a pinion upon a compound register wheel bearing shaft, an actuating shaft connected to positively turn said spur gear wheel and the compound shaft moved by said spur gear wheel in one direction, means upon said spur gear wheel to determine the extent of rotation of said gear wheel and its connected shaft, and means independent of the actuating shaft connected to return the spur gear wheel and its connected shaft to normal starting position, substantially as described.

63. In a register a spur gear wheel mounted to engage and turn a pinion splined upon a compound register wheel bearing shaft, an actuating shaft connected to positively turn said spur gear wheel in one direction, a series of indices upon said spur gear wheel to co-act with a pointer upon a fixed part of the device to determine extent of rotation of the spur gear wheel and its connected pinion and compound shaft, and a torsion spring connected to return the spur gear wheel and its actuated devices to normal starting position, substantially as described.

64. In a register a compound shaft com-

prising a rotatable section and a non-rotatable section to support register wheels, register wheels upon said compound shaft, means to hold said register wheels from rotation upon the rotatable and non-rotatable sections of the compound shaft, means connected to positively move the compound shaft longitudinally in one direction, a rack bar connected to move with the shaft, a pinion engaging said rack bar, and a spring connected to the pinion to turn said pinion backward to move the shaft to normal starting position when said shaft has been released from its positively actuating mechanism, substantially as described.

65. In a register a rotatable stop bearing shaft, a casing partially surrounding said shaft for a part of its extent, a series of equi-sized and spaced indents in said casing having abutting shoulders extending at right angles to the axis of the shaft, a spring to exert continuous rotary pressure in one direction upon said shaft, and a series of ratchet teeth formed in said shaft, in combination with a pawl to engage the ratchet teeth, an actuating shaft to move said pawl to rotate the shaft, a device to move the pawl from connection with the ratchet teeth when the shaft has been turned a predetermined distance, a register wheel bearing shaft, and an arm connected to said shaft to engage the abutting shoulders of the indents in the casing of the stop bearing shaft, substantially as described.

66. In a register a two part recording wheel comprising a central portion to embrace a shaft and a rim to surround said central portion, a register wheel bearing shaft to support said recording wheel, a device to hold the recording wheel from rotation upon said shaft, and means actuated by said shaft to hold the parts comprising the recording wheel locked together when the shaft is turned to move said wheel to position, substantially as described.

67. In a register a two part recording wheel comprising a central part having indents equi-spaced about its central aperture and a rim to surround said central part and having indents equi-spaced about its central aperture, a shaft to support said wheel and having a spline to engage the indents in the central part of said two part wheel, a device upon the central portion of the wheel to engage the indents in the rim of said wheel, and means actuated by the shaft to maintain said device in engagement with an indent in the rim to hold the parts comprised in the recording wheel locked together when the shaft is turned to move said wheel to position, substantially as described.

68. In a register a two part recording wheel comprising a central part apertured to embrace a wheel supporting shaft and a rim to surround said central part, a series of

- equi-spaced indents in the central part to engage a spline upon the wheel supporting shaft, a series of equi-spaced indents in the rim to engage a movable spur carried by 5 the central part of the wheel, in combination with a supporting shaft, a spline in said shaft to engage the indents in the central part of the wheel, and a tooth upon said shaft to contact with the movable spur of 10 the central part of the wheel to hold said spur in an indent in the rim when the shaft is turned to move the wheel to position, substantially as described.
69. In a register a compound shaft comprising a rotatable section and a non-rotatable section, a series of teeth upon the rotatable section to engage indents formed in a recording wheel, supported by said shaft, and splines in each of the rotatable and non- 15 rotatable sections comprised in the shaft, in combination with a two part recording wheel comprising a central part having indents to engage the teeth and splines of the compound shaft and a rim having indents 20 to engage a movable spur carried by the central part of the wheel, and means to move said shaft into engagement with a desired wheel and to rotate said wheel, substantially as described.
70. In a register a compound shaft comprising a rotatable section and a non-rotatable section, a spline extending from end to end of each of said rotatable and non-rotatable sections, a series of projecting 25 teeth surrounding one end of the rotatable section and equi-distant each from the other, means to move the shaft in longitudinal direction, and means to rotate the rotatable section of said shaft, in combination with a 30 series of recording wheels upon the shaft, and transfer devices connected to move a recording wheel forward a predetermined distance when the next adjoining positively actuated wheel has reached a predetermined 35 point in its revolution, substantially as described.
71. In a register a two part recording wheel comprising a central part having an aperture formed therethrough to receive a shaft and a rim movable upon said central part, a series of indents in the central part about the aperture therethrough to engage a spline upon a shaft, a series of indents about the central aperture of the rim to engage a 40 spring supported locking spur connected to the central part, and said spring supported locking spur, in combination with a shaft having a rotatable and a non-rotatable section, splines upon each of said rotatable and 45 non-rotatable sections to engage the indents in the central part of the recording wheel, teeth equi-spaced about the rotatable section of the shaft to extend into the indents in the central part of said recording wheel to hold 50 the locking spur in engagement with the in- 55 dents in the rim of said wheel, means to move the rotatable section of the shaft and teeth thereon into engagement with a desired recording wheel, and means to rotate said rotatable section and the recording 60 wheels thereon, substantially as described.
72. In a register recording wheel a central part having an aperture in its middle to receive a shaft, a series of indents formed in said central part about the aperture therein to engage a spline upon a shaft, a ring mounted and movable upon the central part, a series of indents in said rim to engage a locking spur that is connected to the central part of the wheel, a series of teeth upon the rim to be engaged by a transfer pawl, said transfer pawl, and means to actuate said transfer pawl to turn the rim a predetermined distance, substantially as described.
73. In a register a recording wheel having a central part to be turned a predetermined distance by its supporting shaft, a rim upon said central part to be locked to said central part through connections carried by said shaft, a series of teeth upon one side of said rim to be engaged by a transfer pawl, a stud upon the opposite side of said rim to contact with and move a vertically movable bar, and connections between said bar and a transfer pawl, substantially as described.
74. In a register a transfer mechanism comprising a vertically movable bar connected to be contacted and moved by a stud upon a recording wheel, a transfer pawl to engage teeth upon a recording wheel, a bell crank lever hinged to the vertically movable bar and transfer pawl to move said pawl and the recording wheel in contact with said pawl, and means to move the pawl actuating bar from contact with the stud upon the recording wheel, substantially as described.
75. In a register transfer mechanism a vertically movable bar having its upper end inclined to co-act with an inclined guide by which said bar is moved into the path of a stud upon a register wheel to be moved by said stud, said inclined guide, means to move said bar from contact with the stud upon the wheel, a spring to return said bar to its highest position and into the path of the stud, a transfer pawl, and connections between said bar and said pawl to move said pawl when the bar is moved, substantially as described.
76. In a register transfer mechanism a vertically movable bar having an inclined upper end to be engaged by a stud carried by a register wheel, and a forwardly and downwardly projecting lower end upon said bar to contact with a fixed part of the register to swing the bar from engagement with the stud, in combination with a transfer pawl to be moved to contact with teeth

upon a register wheel to turn said wheel, a device carried by said pawl to determine the extent of movement of a wheel moved by said pawl, connections between said pawl and its actuating bar to move said pawl, and means to move the bar upwardly and its connected pawl from engagement with the teeth upon the register wheel, substantially as described.

5 77. In a register transfer mechanism a horizontally movable transfer pawl, a projection upon the top of said pawl to extend between adjacent teeth of a register wheel, and an inclined guide track to hold the 10 pawl in contact with the wheel, in combination with a vertically movable bar to be engaged and moved by a stud upon the register wheel, connections between said bar and said transfer pawl to move the pawl by said 15 bar, and means to move the bar upwardly to withdraw the pawl from connection with the register wheel, substantially as described.

78. In a register a recording wheel bearing shaft, a device upon said shaft to turn a recording wheel mounted on said shaft, a series of recording wheels upon said shaft, means to move the recording wheel actuating device on the shaft into engagement 25 with a desired wheel of said series, transfer mechanism to record tens of units upon a recording wheel of higher denomination than the wheel acted upon by the shaft, and means connected to move said transfer 30 mechanism from operative connection with the wheel acted upon by the shaft and all the recording wheels of lower denomination than the wheel so acted upon, substantially as described.

40 79. In a register a compound shaft comprising a rotatable section and a non-rotatable section, a series of recording wheels upon said shaft, means to hold the wheels from rotation independent of the shaft, a 45 device to move the rotatable section of the compound shaft into engagement with a desired one of the recording wheels upon the compound shaft, transfer mechanism connected to be operated by the wheel of highest 50 denomination upon the rotatable section, and means moved by the compound shaft to release the transfer mechanism from recording wheels of lower denomination than that so actuating the transfer mechanism as noted, substantially as described.

55 80. In a register a compound shaft comprising a rotatable section and a non-rotatable section, a series of recording wheels upon said compound shaft, means interposed between said shaft and the recording wheels thereupon to hold the wheels from rotation independent of said shaft, transfer mechanism connected to be operated by a wheel of low denomination to move a wheel 60 of higher denomination, and a bar connect-

ed to be moved into contact with the transfer mechanism of each recording wheel upon the rotatable section of the compound shaft to move said transfer mechanism from operative connection with said recording 70 wheels, substantially as described.

81. In a register a compound shaft comprising a rotatable section and a non-rotatable section, a series of recording wheels upon said compound shaft, means to hold 75 said recording wheels from rotation independent of the shaft upon which they are mounted, means to move the shaft in longitudinal direction to bring the rotatable section of said shaft into engagement with a 80 desired recording wheel, and means to turn the rotatable section to a predetermined extent, in combination with transfer mechanism to be operated by a wheel of low denomination to move a wheel of higher 85 denomination, and a bar connected to the shaft to move in longitudinal direction with said shaft to hold the transfer mechanism from turning the recording wheels upon the rotatable section of the compound shaft, as 90 set forth.

82. In a register a series of symbol bearing wheels, connections to hold said wheels normally locked from rotation, an operating mechanism normally out of engagement 95 with the symbol bearing wheels to move said wheels, connections to establish operative engagement between said operative mechanism and said wheels, means whereby said operative mechanism is first caused to turn the wheel of highest denomination in the amount to be registered and thereafter to successively turn the wheels of the next lower denomination, and means to return said wheels to locked position, substantially 100 as described.

83. In a register a series of symbol bearing wheels, a compound shaft to support and actuate said wheels, connections upon said shaft to hold said wheels normally 110 locked from rotation, an actuating mechanism normally out of engagement with the symbol bearing wheels, means to positively move the actuating mechanism into operative connection with a symbol bearing 115 wheel, means to thereafter move said actuating mechanism into operative connection with wheels of lower denomination, means to lock the symbol bearing wheels from rotation after they have been acted upon by 120 the actuating mechanism, and means to return the actuating mechanism to its normal starting position, substantially as described.

84. In a register a series of symbol bearing wheels, a compound shaft to support 125 said wheels, an actuating mechanism to operate a rotatable section of said compound shaft to turn said symbol bearing wheels, means to positively move the rotatable section of the shaft into operative connection 130

with the wheel of highest denomination in the amount to be registered, and means moved by said actuating mechanism to move the rotatable section of the shaft into operative connection with wheels of lower denomination, substantially as described.

85. In a register a series of symbol bearing wheels, a compound shaft to support said wheels, an operating mechanism comprising a rotatable section of the compound shaft to turn the symbol bearing wheels, means to positively move said operating mechanism into operative engagement with the wheel of highest denomination to be actuated, and means to move said operating mechanism in step by step movement successively into engagement with wheels of lower denomination, substantially as described.

86. In a register a series of symbol bearing wheels, a compound shaft comprising a rotatable section and a non-rotatable section upon which said symbol bearing wheels are mounted, means to move the rotatable section of the compound shaft into operative connection with a selected wheel and simultaneously release said selected wheel and all wheels of lower denomination other than said selected wheel from restraint other than that exerted by the rotatable section of the compound shaft, and means to release said wheels from the rotatable section of the shaft, substantially as described.

87. In a register a series of symbol bearing wheels, a compound shaft comprising a rotatable section and a non-rotatable section in alignment each with the other to support the symbol bearing wheels, means to move the rotatable section of the compound shaft into operative connection with a selected wheel and to simultaneously release said selected wheel and all wheels of lower denomination than said selected wheel from restraint other than that exerted by the rotatable section of the compound shaft, means to move the rotatable section of the compound shaft in step by step movement from wheels of higher to wheels of lower denomination, and means to lock the wheels from rotation when released from the rotatable section of the compound shaft, substantially as described.

88. In a register a series of symbol bearing wheels, transfer mechanism to be moved by wheels of low denomination to move wheels of higher denomination, a compound shaft comprising a rotatable section and a non-rotatable section upon which the symbol bearing wheels are supported, means to move the rotatable section of the compound shaft into operative connection with a selected wheel and to simultaneously release said selected wheel and all wheels of lower denomination other than said selected wheel from the transfer mechanism and from all

restraint other than that exerted by the rotatable section of the compound shaft, and means to release the rotatable section in step by step movement from connection with the wheels, substantially as described.

89. In a register a series of symbol bearing wheels, transfer mechanism connected to be moved by wheels of low denomination to move wheels of higher denomination, a compound shaft comprising a rotatable section and a non-rotatable section to support said wheels, mechanism to move the compound shaft in longitudinal direction to bring the rotatable section of the compound shaft into operative connection with a selected wheel, connections actuated by the movement of the compound shaft to move the transfer mechanism from operative connection with the symbol bearing wheels while said wheels are upon and turned by the rotatable section of the compound shaft, and means to return the rotatable section of the compound shaft to its normal position and out of connection with the wheels, substantially as described.

90. In a register a series of symbol bearing wheels rotatably mounted upon a compound shaft provided with a rotatable section and a non-rotatable section, an actuating mechanism to move the rotatable section of the shaft into position to turn said wheels, means to positively cause the actuating mechanism to move the rotatable section of the compound shaft into operative connection with a selected symbol bearing wheel, means operated by said actuating mechanism to move the rotatable section of the shaft successively into connection with wheels of lower denomination, and means to hold the symbol bearing wheels from rotation when said wheels are released from the operating mechanism noted, substantially as described.

91. In a register a series of symbol bearing wheels, a compound shaft having a rotatable section and a non-rotatable section to support said wheels, an actuating mechanism to operate the rotatable section of the shaft to turn said symbol bearing wheels, means set in action by the actuating mechanism to positively move the rotatable section into connection with a selected symbol bearing wheel, means operated by said actuating mechanism to move said rotatable section into connection with wheels of lower denomination through a step by step movement, means to hold the symbol bearing wheels from rotation when released from the rotatable section of the shaft, and means to return the actuating mechanism and the rotatable section of the shaft to their normal starting position, substantially as described.

92. In a register a compound shaft comprising a rotatable section to turn a register wheel and a non-rotatable section to hold a

- register wheel from rotation, a series of register wheels mounted upon a compound shaft to be actuated thereby, means to retain the register wheels from lateral movement when acted upon by the compound shaft, and means to independently move the rotatable and the non-rotatable section of the shaft to actuate a predetermined register wheel, substantially as described.
93. In a register a compound shaft comprising a rotatable section to turn a register wheel and a non-rotatable section to hold a register wheel from rotation, a series of register wheels mounted upon said compound shaft to be actuated thereby, means to hold the register wheels from lateral movement during the action of the compound shaft thereon, a device to move the shaft longitudinally to bring the rotatable section of said shaft into operative engagement with a predetermined register wheel, and means to determine the extent of rotation of the rotatable section, substantially as described.
94. In a register a compound shaft comprising a rotatable section to turn a register wheel and a non-rotatable section to hold a register wheel from rotation, a series of register wheels mounted upon said compound shaft to be actuated thereby, means to hold the register wheels from lateral movement during the action thereon of the compound shaft, a device to move the shaft longitudinally to bring the rotatable section of said shaft into operative engagement with a predetermined register wheel, mechanism to turn the rotatable section to rotate the register wheel, means to positively determine the extent of rotation of the rotatable section, and means to return the rotatable section and the shaft of which it is a part to its normal starting position and to maintain the register wheel acted upon by the rotatable section of the shaft in the position to which it was turned, substantially as described.
95. A rotatably supported register wheel having an aperture formed therethrough, a compound shaft comprising a rotatable section and a non-rotatable section extending through the aperture in said register wheel, and means to alternately move the rotatable and the non-rotatable sections of the compound shaft into operative connection with said register wheel to turn said wheel and thereafter to hold said wheel from turning, substantially as described.
96. A plurality of rotatably supported register wheels each thereof having an aperture formed therethrough, a compound shaft comprising a rotatable section and a non-rotatable section extending through the apertures in said wheels and common to each thereof, and means to move the rotatable section of the compound shaft into operative

connection with a desired one of said register wheels to rotate the same, substantially as described.

97. A rotatably supported register wheel having an aperture formed therethrough, a compound shaft comprising a rotatable section and a non-rotatable section extending through said wheel, a device upon each of said rotatable section and non-rotatable section of the compound shaft to move with said sections into connection with the wheel to hold the desired section in operative connection with said wheel, and means to move the selected section of the compound shaft into operative connection with said register wheel, substantially as described.

98. A plurality of rotatably supported register wheels each thereof having an aperture formed therethrough, a compound shaft comprising a rotatable section and a non-rotatable section to extend through the aperture in each of said wheels, a device upon each of the rotatable and non-rotatable sections of the compound shaft to engage a desired one of said wheels, and selective means connected to move the rotatable section of the compound shaft and the device thereon into operative connection with a desired one of the wheels, substantially as described.

99. A plurality of rotatably supported register wheels each thereof having an aperture formed therethrough for the passage of a compound operating shaft, a compound operating shaft comprising a rotatable section and a non-rotatable section extending through and common to each of said wheels, a device upon each of said rotatable and non-rotatable sections of the shaft to operatively connect either desired of said sections to either desired of said wheels, selective means connected to move the compound shaft longitudinally and the device upon the rotatable section of said shaft into operative connection with the desired one of the register wheels to move said wheel, and means independent of said selective mechanism to turn the rotatable section of the shaft and the wheel thereon a desired distance, substantially as described.

100. A plurality of rotatably supported register wheels each thereof provided with an aperture therethrough for the passage of an operating shaft, a compound operating shaft comprising a rotatable section and a non-rotatable section to extend through the apertures in said register wheels, a device upon the rotatable section of said compound shaft to connect said shaft to either desired of the wheels to rotate the wheel, a device upon the non-rotatable section of the shaft to engage a register wheel to hold said wheel from rotation, selective means to move the compound shaft longitudinally and the ro-

latable section thereof into operative connection with a desired one of the register wheels, mechanism to turn the rotatable section of the compound shaft and the wheel thereon to a desired extent, and means to return the rotatable section of the compound shaft to normal position, and to move the non-rotatable section of the shaft into connection

with the register wheels to hold the same from rotation, substantially as described. 10

In testimony whereof I hereto affix my signature in presence of two witnesses.

WILLIAM H. H. KNIGHT.
